UNITED STATES PATENT OFFICE.

ALBERT HANSEN AND MORTEN J. TORP, OF HARLAN, IOWA.

GOVERNOR FOR EXPLOSIVE ENGINES.

Application filed March 17, 1927. Serial No. 176,252.

The present invention is directed to improvements in governors for explosive engines.

The primary object of the invention is to provide a device of this character so constructed that it can be quickly attached to the cam shaft of the engine and when in place will automatically control the throttle valve in order that the motor will be prevented from operating beyond a predetermined speed.

Another object of the invention is to provide a governor so constructed that it can be attached to the cam shaft of the engine upon simply removing the usual cam shaft nut and drilling an opening in the shell of the distributor unit.

In the accompanying drawing:

Figure 1 is a fragmentary side elevation 20 of a tractor engine, showing the device in place thereon.

Figure 2 is a vertical sectional view through the governor and cam shaft connection.

Figure 3 is a front elevation of the device.

Figure 4 is a sectional view through the governor casing.

Referring to the drawings, 1 designates 30 an engine, 2 the cam shaft thereof, and 3 the distributor, which as customary, is provided with a protecting shell 4.

The forward end of the cam shaft is threaded, as at 5, for the reception of the 35 usual holding nut, which is removed when our governor is attached, there being an opening 6 formed in the shell 4, the purpose of which will be later explained.

A spindle 7 is employed and has its rear 40 end provided with a head 8 having a threaded socket 9 therein for engaging the threaded end of the cam shaft 2, as clearly shown in Figure 2 of the drawing, the spindle being extended through the opening 6 of the shell 4.

The spindle 7 is provided with an axial bore 8' in which is slidably mounted a rod 9', said rod having a cone 10 formed thereon, and extending from the major end 50 of the cone is a pin 11, the purpose of which will later appear.

The governor casing 12 includes a collar 13 which is engaged upon the spindle 7 and retained in place thereon by a set screw 14.

The governor weights 15 consist of angu-

larly disposed arms 16 and 17, the latter constituting weights swingable outwardly by centrifugal force in order that the arms 16 will move inwardly for engagement with the cone.

These arms are pivotally supported upon opposite sides of the cone 10 by studs 18 and are maintained in their inoperative position by coil springs 19 which have one 65 of their terminals connected to the arms 17 and their other terminals secured to the back wall 20 of the casing 12.

The arms 16 have terminal heads 21 which are provided with beveled faces 22 70 which are in a plane with the beveled surface of the cone 10, but normally disengage therefrom, as shown in Figure 2 of the drawing.

The cover plate 23 is secured upon the 75 open side of the casing 12 by screws 24, said plate having a central bearing 25 in which the pin 11 is slidably engaged for contact with the arm 26. This arm has its lower end fixed to a rock shaft 27 supported by the bracket 28 which may be supported in any suitable manner on the tractor frame. To the outer end of the shaft 27 is fixed the lever 28 having the forward end of a link 29 pivotally connected to its upper end, said link having its rear end connected with the usual 80 throttle valve of the engine, not shown.

It will be obvious that as the speed of the cam shaft increases, the arms 17, by 90 centrifugal force will swing outwardly, doing which causes the arms 16 to swing inwardly, whereupon the beveled faces 22 of the head 21 will engage the beveled surface of the cone, thus forcing the cone outwardly. As the cone moves outwardly, the pin 11 will rock the arms 26, thereby rocking the shaft 27, likewise the lever 28, which through the medium of the link 29, the throttle valve will be operated to reduce the 95 flow of fuel, thus reducing the speed of the engine. As the speed of the engine decreases the springs 19 will move the governor weights to their normal or inoperative position and will remain thus until the 100 speed is again increased.

Since the weights 15 are pivotally mounted for movement at right angles to the longitudinal axis of the spindle 7 the device can be compactly arranged and consequently can be placed in a restricted 110 space.

Having thus described the invention, we claim:

A governor for explosive engines, in combination with the cam shaft and throttle valve thereof, said cam shaft having a threaded end, a distributor associated with the cam shaft and including a shell having an opening therein, a spindle engaged in said opening and having a head for detachable engagement with the threaded end of the cam shaft, a casing rotatable with the spindle, governor weights pivotally mounted in the casing and including angularly

disposed arms, certain of the arms having beveled faces, a cone carried by the spindle, a pin carried by the cone, the governor weights being operable by centrifugal force to cause the beveled faces to engage the cone to slide the pin, and means operable by the pin for controlling the movement of the throttle valve.

In testimony whereof we affix our signatures.

ALBERT HANSEN. [L. S.]
MORTEN J. TORP. [L. S.]
